[57] **CLAIM**

The ornamental design for a golf cart, as shown and described.

DESCRIPTION

FIG. 1 is a front elevational view of the golf cart showing my new design;

FIG. 2 is a left side elevational view thereof, the right side elevational view being a mirror image of that shown;

FIG. 3 is a rear elevational view thereof;

FIG. 4 is a top plan view thereof;

FIG. 5 is a bottom plan view thereof; and

FIG. 6 is a right side elevational view thereof, showing the top of the golf bag open.

FIG. 1FIG. 2FIG. 3

FIG. 4

FIG. 5

FIG. 6
